UNITED STATES PATENT OFFICE

150,808

DESIGN FOR A VEHICLE HOOD ORNAMENT OR SIMILAR ARTICLE

Theodore W. Pietsch, Royal Oak, Mich., assignor to Packard Motor Car Company, Detroit, Mich.,
a corporation of Michigan

Application May 24, 1947, Serial No. 139,249

Term of patent 14 years

(Cl. D14—18)

To all whom it may concern:

Be it known that I, Theodore W. Pietsch, a citizen of the United States, residing at Royal Oak, county of Oakland, State of Michigan, have invented a new, original, and ornamental Design for a Vehicle Hood Ornament or Similar Article, of which the following is a specification, reference being had to the accompanying drawing, forming a part thereof.

I claim:

The ornamental design for a vehicle hood ornament or similar article, substantially as shown.

THEODORE W. PIETSCH.
